UNITED STATES PATENT OFFICE

WALTER EDWIN OTWELL, OF LINN, KANSAS

RADIATOR CAP

Application filed November 12, 1928. Serial No. 318,986.

This invention relates to improvements in radiator caps, or apparatus carried thereby.

The primary object of this invention is the provision of an improved emblem or device adapted to be part of a radiator cap for positioning over the top water inlet openings of automobile radiators, and which has improved means thereon to permit the efficient determination of the thermal efficiency of the water within the radiator.

A further object of this invention is the provision of an improved radiator cap, which includes an ornament or emblem which may be characteristic of the emblem adopted by the manufacturer of the car upon which the cap is to be used; the emblem having characteristic means thereon which may be common to any number of different emblems, to display the slogan or name of the car or manufacturer of the car at the front thereof; the improved cap having means associated in a novel relation therewith to illuminate a compartment wherein the rays of light throw the slogan or name into relief; the improved device having a thermometer associated therewith in an efficient and illuminated relation for determining the temperature of the water in the radiator upon which the cap is positioned.

Other objects and advantages of this invention will be apparent during the course of the following detailed description.

In the accompanying drawing, forming a part of this specification, and wherein similar reference characters designate corresponding parts throughout the several views,

Figure 1 is a front elevation of the improved device adapted to be detachably connected upon a radiator cap, or rigidly attached as a part of the cap.

Figure 2 is a rear view of the device of Figure 1, showing parts in section.

Figure 3 is a cross sectional view taken through the improved radiator cap structure, substantially on the line 3—3 of Figure 1.

In the drawing, wherein for the purpose of illustration is shown only a preferred embodiment of the invention, the letter A may generally designate the part of the radiator

cap in which this invention lies, which may include a base 10 having a bottom plane surface 11. Centrally from the base 10 depends a hollow screw threaded shank 12 which may be slipped through a suitable opening 55 in an ordinary cap base (not shown); nut 14 being adjustable thereon to clamp beneath the top wall of the cap to attach the apparatus A upon the cap base, in a manner which is well understood.

In the preferred arrangement the base 10 may have integrally cast or otherwise connected therewith spaced wings 17 and 18, which arcuate upwardly in spaced relation and then inwardly at their apices 19, to provide a sort of opening or area 20 wherein it is desired to connect certain parts of the invention to be more fully described. The wings 17 and 18 are formed as a body which has a compartment 21 therein immediately 70 above the base 10; the compartment 21 extending upwardly along the wings 17 and 18. This compartment is open at the rear of the wings, and a detachable cover plate 22, shaped to conform with the outline of the 75 wings 17 and 18, above the base 10, is provided, and adapted to be detachably connected to the margins of the wings 17 and 18 by screws 24, to close the compartment 21.

In axial alignment with the shank 12, the 80 casting is provided with a sort of frustoconical shank 25, extending upwardly into the space between the wings 17 and 18, and upon which is integrally or otherwise connected laterally extending arms 27 and 28, 85 which respectively extend towards the wings 17 and 18, and may be connected therewith, if desired. A compartment 30 is provided in the upper part of the shank 25, which extends into the arms 27 and 28, but which is separated from the compartment 21 except by means of an opening through which a thermometer stem 31 extends; this stem 31 being suitably connected on the base 10 and at its lower end extending into the hollow screw 90 threaded shank 12, and thence upwardly through the compartment 21 and vertically into the compartment 30, as shown in Figure 2, terminating short of the top wall 35 above the compartment 30. This thermometer stem 100

31 is of the usual construction, being of transparent material, wherein a contrasting colored fluid, such as alcohol is received, which has a high coefficient of expansion under 5 temperature variation.

The rear of the casing containing the compartment 30 is open, and over which a translucent or opaque glass cover 40 is adapted to be positioned, and held in place by means of 10 a marginal strip of metal 41, which is held in place by screws 42. This plate 40 may be clamped against a flexible gasket if desired. A vertical strip 44 of the glass plate 40 is transparent, immediately to the rear of the 15 upper end of the thermometer stem 31, thru which the thermometer stem is visible from the driver's seat of the vehicle, to determine the temperature of the water in the radiator upon which the cap is positioned. Otherwise 20 the rear surface of the plate 40 is opaque at 44^a. The front wall of this casing, shown at 47 in Figures 1 and 3 of the drawing, may be suitably provided with stencil-like openings 48, in the form of letters or other indicia pertinent to the car or other article or matter 25 which the cap is adapted to represent or advertise. In this front wall 47 is also provided an opening 50 between the arms 27 and 28, immediately at the front of the upper 30 portion of the thermometer stem 31, as a means of admitting a clear vision of the thermometer stem, during daylight travel, and to afford a view of the thermometer stem 35 from the front of the vehicle.

The end walls 55 and 56 of the arms 27 and 28 are provided with sockets 58 adapted to receive electric light bulbs 60, by means of which to illuminate the compartment 30 at both sides of the thermometer stem 31, so that 40 it may be readily visible thru the openings 44 and 50. The wires 61 from the bulb sockets 58 extend transversely thru openings in the casing walls of the emblem wings 17 and 18, and extend downwardly through the compartment 21, passing through an opening 63 in the base 10, leading to any suitable location, preferably and inserting plug 65, as shown in Figure 2.

It is apparent from the foregoing that a 50 novel radiator cap has been provided, embodying important structural features which will permit the cap to display an emblem or other insignia in such manner that an illuminated compartment may display advertising or other data to the front of the vehicle, and 55 and illuminate a water temperature indicator so that the driver of the vehicle may readily observe the same.

Various changes in the shape, size, and 60 arrangement of parts may be made to the form of invention herein shown and described, without departing from the spirit of the invention or the scope of the claims.

I claim:

65 1. In a radiator cap of the class described

a supporting base, spaced wings carried by the base extending upwardly therefrom in spaced relation, a horizontally elongated casing mounted between and engaging said wings at its ends and having a separate compartment therein, a thermometer connected with the base and extending upwardly into the casing at its upper end, and illuminating means in the casing for illuminating the thermometer, the rear wall of the casing being 70 transparent to permit the thermometer in the casing to be seen.

2. In a radiator cap of the class described a supporting base, spaced hollow wings carried by the base extending upwardly therefrom in spaced relation, a casing mounted between said wings having a separate compartment therein, a thermometer connected with the base and extending upwardly into the casing at its upper end, illuminating 75 means in the casing for illuminating the thermometer, electric lamp bulbs in opposite ends of the casing adjacent said wings, and electric conducting cords connected with the lamps and extending downwardly through 80 said wings to the base and exteriorly thereof.

3. In a radiator cap the combination of a base, hollow wings carried by the base joined at the bottom and extending upwardly in spaced arcuated relation, said wings having compartments opening above the base, a casing carried at the juncture of the wings and disposed therebetween and having a compartment therein separate from the wing compartments, said casing having openings 95 therein, electric bulbs within said casing, and wires leading to said bulbs extending into the compartments of the wings and outletting at the base.

4. In a radiator cap a base, hollow wings extending upwardly from the base having compartments joined above the base and open at the rear of said wings, a plate closure for the rear of the compartments of said wings, a casing carried at the juncture of the wings and extending between the wings having a compartment therein separate from the compartments of the wings, and a rear wall detachably connected over the casing to close the same having a transparent wall.

5. In a radiator the combination of a base, a support upon the base having a compartment therein open at the rear thereof, a detachable plate for the support to close said compartment, a casing mounted upon said support having a compartment therein separate from the compartment of the support, the compartment of the casing being open at the rear thereof, a plate detachably connected on the casing having a transparent portion thereon to expose the interior of the casing, a heat indicator extending into the compartment of the casing, electric illuminating means in the casing to illuminate the interior thereof, and wires for the illuminat-

ing means extending into the compartment of the support and through the same exteriorly thereof.

6. In a radiator cap the combination of a
5 supporting base having a pair of hollow
wings mounted directly thereon and extending
upwardly in relatively spaced relation
arcuating upwardly convergently, the hollow
wings above the base having an upward pro-
jection in the space at the juncture of said
wings, a hollow casing mounted on said pro-
jection having laterally extending arms ex-
tending across the space to adjacent the re-
spective adjacent wings, electric lamps in the
15 casing at the ends of said arms, connecting
wires connected with said electric lamps and
extending outwardly from the arms of the
casing into the wings and downwardly
through the hollow of the wings and outlet-
20 ting laterally from said base, and closure
means for said casing and said wings.
